UNITED STATES PATENT OFFICE

2,033,652

HIGH COLONIC THERAPY INSTRUMENT

Nicholas B. Salerni, Indianapolis, Ind.

Application August 31, 1931, Serial No. 560,298
Renewed June 2, 1934

17 Claims. (Cl. 128—244)

The object of this invention is to provide a rectal expanding nozzle with a suitable valve, which will give the maximum of results in the irrigation of any body cavity, human or animal, or cavity of any sort or nature not necessarily confined to the animal or human body.

A further object is to provide an expanding nozzle which will so fit any cavity as to cause an automatic retention of the nozzle in place, so that there is no danger of its slipping out to release fecal matter to soil garments and linen or discharge odors in the treatment room.

The object, further, is to increase the diameter of the bore of the nozzle to provide a greater return flow or drainage, which is a most important part in irrigation, particularly of the colon.

A further object is to provide an instrument of medium initial diameter for introduction in the rectum because of the contraction of the sphincter muscle caused by such introduction and an instrument which can be manipulated to enlarge the diameter after a few minutes insertion to conform with the relaxed condition of that muscle which always follows, and by such enlargement of the instrument prevent the escape of matter around it from the bowels, particularly when the colon or cavity is distended with an injected fluid.

A further object is to provide such valve control over the instrument that the operator can completely close all flow therethrough, open for an intake flow only, or for an out drain only, or for simultaneous intake and drainage as for continuous irrigation.

I accomplish the above and other objects which will hereinafter appear, by the mechanism illustrated in the accompanying drawings, in which

Fig. 1 is a view in side elevation and partial longitudinal section at places to show the internal structure of one form of my instrument showing a rotary expandible nozzle.

Fig. 2 is a cross section on the line 2—2 of Fig. 1.

Fig. 3 is a side elevation and partial section of a modified form of instrument showing a non-expandible nozzle and colon tube located externally of the cylinder.

Fig. 4 is a cross section on the line 4—4 of Fig. 3.

Fig. 5 is a side elevation of a second modified form with an expandible nozzle which is expanded by internal pressure.

Fig. 6 is an end view of the instrument looking at the end opposite the nozzle.

Fig. 7 is a detail in longitudinal section on the line 7—7 of Fig. 5 showing the valve gear control.

Fig. 8 is a cross section on the line 8—8 of Fig. 5, and

Fig. 9 is a detail in longitudinal section of a modified form of valve mechanism for my instrument.

Like characters of reference indicate like parts in the several views of the drawings.

Referring to Figs. 1 and 2 of the drawings, the nozzle represented as a whole by the numeral 1, is the part that enters the cavity. It is attached to a cylindrical sleeve 2 which is mounted on the end of a body 10 and has a rocking adjustment thereon regulated in extent by a circumferential slot 3, through which is passed a screw 4, seated in the body 10. A regulated adjustment of the sleeve is obtained by a pinion 5 engaging a series of indents 6 in the sleeve 2. The pinion is on a shaft 7 extending longitudinally of the body 10 and terminating with a milled wheel 7' for manipulation. An index 8 on the sleeve 2 points to a scale 9 on the body so that the rotation of the sleeve and accompanying enlargement or reduction of the nozzle may be gauged.

An end of the sleeve is finished with a roll in which knobs on the ends of a series of curved wire ribs 30 are hinged. The ribs 30 pass loosely through holes in a ring 31 fixed to the end of the barrel 10 in a manner to be fulcrumed in the ring. The ribs are curved or bowed between the ring and the distal end of the instrument in a manner to cause the ribs to be spread apart and expanded as a whole by rocking the sleeve 2 in one direction and to be retracted or drawn together when the sleeve is rocked in a reverse direction.

Preferably, and as shown in Fig. 1, the ribs as a whole are contained within a cover 32, here shown as elastic rubber which stretches and contracts and folds and unfolds, as the ribs are distended or are drawn together. The cover at the small end generally folds more or less, as shown by the longitudinal lines, in the reduced form of the nozzle. An obturator of usual construction (not shown) is used during the introduction of a rigid nozzle to prevent injury, as shown in Fig. 3.

Referring now to the rest of the instrument, the body or barrel 10 has a cylindrical bore and a slightly tapering end adjacent to the ring 31. It has a drain nipple 11 and an intake nipple 12.

Seated in the barrel 10 is a piston 13 which has a transverse diametrical slot 14 in its distal end for drainage purposes. It terminates outside of the barrel with an enlarged head which is milled for convenient manipulation in rotating the piston. The piston also has a circumferential groove which receives a set screw to provide mo-

tion of rotation without translation, of the piston in the barrel.

Two intake holes 15 and 16, here shown as 90° apart, are provided in the piston and are connected by a groove as shown by dotted lines in Fig. 1. These holes make connection with the intake nipple 12 of the barrel and selectively with a nipple 17 on the outer end of the piston. The nipple 17 is in the piston at one side of and parallel with a center hole 18. A colon tube 19 is passed through the hole 18 and extends through the nozzle at the distal end of the instrument. A packing gland 20 prevents any back movement of the tube and escape of fluid around the tube from the instrument. The tube 19 is continued in a curve and is attached to the nipple 17.

In the operation of my instrument, after the nozzle has been introduced into the cavity and expanded to a condition of closure to prevent leakage, liquid, medicated or not, as desired, is admitted through the intake nipple 12, from any suitable source (not shown) regulated by any suitable valve (not shown) and by rocking the piston 13, the liquid will pass through the colon tube 19 into the cavity. The discharge through nipple 11 is regulated by a suitable valve, formed by barrel 10 and piston 13 so that, by opening this valve a flow will occur through barrel 10 and slot 14 into the nipple 11. By properly turning the piston 13 the intake and outlet may also be closed or opened.

In the modification shown in Fig. 3, the ordinary rigid non-expansive nozzle is shown just to illustrate that possibility although the expansible nozzle is preferred. The barrel 10^a has a large drain 11^a and two nipples 12^a and 12^b for intake and discharge, respectively. These are here shown as in a row longitudinally of the barrel, but they may be separated circumferentially by 90°, (not shown). Outside of the barrel is a tube 21 which serves for a holder and passage therethrough of a colon tube 19^a which enters the barrel itself near the distal end by bending the barrel in the manner shown. This tube 19^a is here located at one side of the two nipples, but would pass between them if the nipples were 90° apart circumferentially of the barrel as above explained. The colon tube 19^a is attached to the intake nipple 12^b, and is passed thence through the pipe 21 and through the nozzle. A piston 13^a has no longitudinal central hole but has a diametrical slot 14^a at the distal end for drainage flow. Two longitudinal channels 22 and 23, 90° apart make connection at different adjustments of the barrel, with the two barrel nipples. A packing gland 24 holds the colon tube in place and prevents back flow around it. In the modification shown in Fig. 5, the distal end of the barrel 10^b has an inside corrugation in which a ring is seated to which ring a plurality of wire resilient ribs 30 are attached. These ribs are bent as shown, into the path of a piston 13^b which has a longitudinal reciprocatory adjustment in the barrel, causing its end to contact the ribs and spread them apart at their outer ends. The ribs are shown as covered by an elastic rubber cover or shield 60 which expands and contracts and folds with the action of the ribs. The ribs may be embedded or otherwise attached to the cover, or the cover may be loose thereon and removable, whereby the ribs may be used covered, or uncovered in which latter form the ribs directly contact the membrane of the cavity in which the instrument is used. The ribs for the nozzle may be wide for half of their base ends, overlapping

each other (not shown) and narrow at their distal ends and used with or without a rubber cover.

It will be seen from foregoing disclosures that I provide a nozzle that can be reduced in size for easy introduction and removal and expanded to stop leakage in use, and that the valve construction affords room for a large discharge. When a colon tube is passed through the customary rigid straight tube the space around the colon tube is so small that only liquids can pass and mucus, seeds, stones, scales, fecal masses hard or soft cannot pass. This defeats the purpose and causes the patient to stool as soon as the instrument is removed, which is not only inconvenient and annoying but discredits the treatment and ability of the doctor. But with my expanding nozzle, the rectum can be expanded to maximum as the sphincter relaxes, and a return flow or drainage can be several times greater than with the rigid or unexpanding tube. With such large return drain all foreign material as mentioned above will pass through without any difficulty. With no material left behind when the nozzle is withdrawn the rectum is free from irritation and the patient does not have to stool immediately as is the case with the unexpanding tube.

The advantage of using one nozzle for all cases, be it children or adults, against three or more of the old unexpanding type, is very great and also less expensive.

The simplicity of my nozzle, of either type, makes it easily attached and removed, easily sterilized like any other surgical instrument or like rubber gloves. The placing of the rubber cover over the nozzle is as simple as putting on a rubber glove over the hand, and can be done in a few seconds.

The piston is formed with grooves 36 which are engaged by a worm 37 on a shaft 38, mounted in a housing outside of and parallel with the barrel 10^b. The shaft 38 terminates with a milled wheel by which it is rotated to impart travel to the piston. The distal end of the piston is hollow back to a transverse diametrical slot 14^b, for the free flow of liquids therethrough, to a drain nipple 11^b. The rest of the valve construction is substantially the same as described for Fig. 3, and need not be here repeated. In the modification of valve mechanism and control shown in Fig. 9, a barrel 18^c has only a drain 11^c. A piston 13^c has a slot for the drain, a center passage for the colon tube and a packing gland 20^c. A selective valve 25 shown and described in my co-pending application controls the fluid flow. The piston is reciprocated by mechanism similar to that shown and described for Fig. 5.

Having thus fully described my invention in the best form now known to me, what I claim as new and wish to secure by Letters Patent, without being confined to the exact structure here disclosed more than is required by the appended claims,

I claim:

1. In an irrigating nozzle, a plurality of ribs in annular series held at corresponding ones of their adjacent ends, fulcrumed between their ends and bent between the fulcrums and ends opposite their held ends and means coacting with said bends for varying the distance apart and spread of the ribs at said bends.
2. In an irrigating nozzle, a plurality of bent ribs in annular series, an elastic cover for the ribs and means coacting with the bends of the

ribs for varying the distance apart of the ribs and for stretching the cover comprising a reciprocating piston movable into contact with the bends.

5 3. In an irrigating nozzle, a plurality of ribs in annular series held at corresponding ones of their adjacent ends, fulcrumed between their ends and bent between the fulcrums and ends opposite their held ends and means for moving the held ends to rock the ribs for varying the distance apart of the bent portions comprising a rotatable sleeve in which the held ends are socketed.

10 4. In an irrigating nozzle, a plurality of ribs in annular series held at corresponding ones of their adjacent ends, fulcrumed between their ends and bent between the fulcrums and ends opposite their held ends, and a reciprocating spreader contacting the bends for varying the distance apart of the last ends, and gear means for accurately reciprocating the spreader.

15 5. In an instrument of the character specified, a barrel having an inlet and an outlet nipple and a third nipple, a movable piston in the barrel having means of liquid communication between the inlet nipple and the third nipple and having a diametrical passage in its distal end adapted to be brought into communication with the outlet nipple by moving the piston, a nozzle on the end of the barrel and a colon tube connected with the third nipple and discharging through the nozzle.

20 6. In an instrument of the character specified, a barrel having an inlet and an outlet nipple, a third nipple, a movable piston in the barrel having means of liquid communication between the inlet nipple and the third nipple and having a diametrical passage in its distal end adapted to be brought into communication with the outlet nipple by moving the piston, a nozzle on the end of the barrel, a colon tube connected with the third nipple and passing through the piston, the barrel and the nozzle.

25 7. In an instrument of the character specified, a barrel having an inlet and an outlet nipple, a third nipple, a movable piston in the barrel having means of liquid communication between the inlet nipple and the third nipple and having a diametrical passage in its distal end adapted to be brought into communication with the outlet nipple by moving the piston, a nozzle on the end of the barrel, a colon tube connected with the third nipple and passing outside of the piston and discharging through the nozzle.

30 8. In an instrument of the character specified, a barrel having an outlet nipple, an expansible nozzle on the distal end of the barrel, a reciprocating piston in the barrel having an end adapted to spread the nozzle, said end having a diametrical slot forming part communication between the nozzle and outlet nipple, a colon tube discharging through the nozzle valve controlled means for supplying liquid to the tube, and manually operated means for reciprocating the piston.

35 9. In an irrigating nozzle, a plurality of ribs in annular series each held at corresponding ones of their adjacent ends, said ribs being bent between the ends and means coacting with the bends for rotating the ribs about their held ends for varying the distance apart of their bent portions.

40 10. In an irrigating nozzle, a plurality of ribs in annular series each held at corresponding ones of their adjacent ends, an elastic cover for the ribs in which the ribs are embedded and which

are expanded by the ribs and by which the ribs are retracted and means to expand and retract the cover by moving the ends of the ribs circuitously.

45 11. In an instrument of the character specified, a barrel having an inlet and an outlet nipple, a third nipple, a movable piston in the barrel having means of liquid communication between the inlet nipple and the third nipple and having a passage in its distal end adapted to be brought into communication with the outlet nipple by moving the piston, the end of said barrel having a discharge opening, a colon tube connected with the third nipple and passing through the piston, the barrel and the barrel discharge opening.

50 12. In an instrument of the character specified, a barrel having an inlet and an outlet nipple and a third nipple, a movable piston in the barrel having means of liquid communication between the inlet nipple and third nipple and having a passage in its distal end adapted to be brought into communication with the outlet nipple by moving the piston, said barrel having an end discharge opening, and a colon tube connected with the third nipple and passing outside of the piston and discharging through the barrel discharge opening.

55 13. A valve having a barrel provided with spaced apart inlet and outlet passages, a shiftable plug in the barrel having at least one passageway adapted to be selectively brought around to provide communication between said barrel passages and to close off both, said barrel being further provided with a drain chamber and an outlet drain passage, said plug being formed to extend over said drain passage to have an end directed toward the chamber and being provided with a passage leading from said chamber from which plug passage lateral openings are provided to control communication between said drain 40 passage and said drain chamber, whereby upon suitable shifting of the plug in the barrel, a selection of flows through the valve may be secured, namely, continuous flow between the barrel passages without drain flow, a complete closure of 45 all barrel and drain passages, a continuous flow between the barrel passages simultaneously with an open barrel drain passage, and a closure of the barrel inlet passage with an open drain passage, said valve being further provided with a 50 passage leading from said barrel outlet passage, and a tube extending from said barrel outlet passage through said drain chamber.

60 14. A valve having a body provided with spaced apart inlet and outlet passages, a shiftable plug 55 in the body having at least one passageway adapted to be selectively brought around to provide communication between said body passages and to close off both, said body being further provided with a drain chamber and an outlet 60 drain passage, said plug being formed to extend over said drain passage to have an end directed toward the chamber and being provided with a passage leading from said chamber from which plug passage lateral openings are provided to 65 control communication between said drain passage and said drain chamber, whereby upon suitable shifting of the plug in the body, a selection of flows through the valve may be secured, namely, continuous flow between the body passages 70 without drain flow, a complete closure of all body and drain passages, a continuous flow between the body passages simultaneously with an open body drain passage, and a closure of the body inlet passage with an open drain passage, and 75

said body being formed to have a colon tube carrying passage entering externally of the body and discharging into said drain chamber whereby the tube may be inserted and carried through the chamber without interference with the operation of said plug.

- 5 15. For an irrigating valve, a body having a central barrel one end of which serves as a drain chamber, an inlet nipple having a passage discharging within the barrel, and a drain nipple having a passage therethrough discharging from said chamber, and means on the barrel for receiving and carrying a tube extending through said chamber.
- 10 16. A valve comprising a barrel having an inlet passage and also an outlet passage, a movable plug in the barrel having at least one passageway adapted to be selectively presented by the plug to provide communication between said barrel inlet and outlet passages and to close off communication therebetween, said barrel having an opening at its forward end and also a drain opening removed from the end, said plug extending over said barrel drain opening and also said plug having a drain passage open at the forward end of the plug and opening from the plug side to selectively communicate with the barrel drain opening upon shifting of the plug, and an injecting passageway carried by the barrel leading from said barrel outlet passage to discharge through the open end of said barrel, whereby upon suitable shifting of the plug in the barrel, a selection of valve controls may be secured namely, an injecting flow without drain into the barrel inlet passage across the plug passage and out the barrel outlet passage and through the injecting passageway out the front end of the barrel, the barrel drain opening being closed; an injecting flow with drainage, the flow being the same as the first flow but with the plug shifted to open the barrel drain opening and provide flow from the barrel end across the plug and out the drain opening; no injection flow, but a drain flow
- 15 20 25 30 35 40

wherein the plug is shifted to close communication between the barrel inlet and outlet openings but leaving the barrel drain open; and no injection and no drain wherein the plug is shifted to close off the barrel outlet passage and also the 5 barrel drain.

17. A valve comprising a barrel having an inlet passage and also an outlet passage, a movable plug in the barrel having at least one passageway adapted to be selectively presented by the 10 plug to provide communication between said barrel inlet and outlet passages and to close off communication therebetween, said barrel having an opening at its forward end and also a drain opening removed from the end, said plug extending over said barrel drain opening and also said plug having a drain passage open at the forward end of the plug and opening from the plug side to selectively communicate with the barrel drain opening upon shifting of the plug, and an injecting 15 passageway carried by the barrel leading from said barrel outlet passage to discharge through the open end of said barrel, whereby upon suitable shifting of the plug in the barrel, a selection of valve controls may be secured 20 namely, an injecting flow without drain into the barrel inlet passage across the plug passage and out the barrel outlet passage and through the injecting passageway out the front end of the barrel, the barrel drain opening being closed; an 25 injecting flow with drainage, the flow being the same as the first flow but with the plug shifted to open the barrel drain opening and provide flow from the barrel end across the plug and out the drain opening; no injection flow, but a drain 30 flow wherein the plug is shifted to close communication between the barrel inlet and outlet openings but leaving the barrel drain open; and no injection and no drain wherein the plug is shifted to close off the barrel outlet passage and 35 also the barrel drain, said first plug passage being confined to a groove in the periphery of the plug. 40

NICHOLAS B. SALERNI.
